CARTON

Bruce J. Davidson, Kew Gardens, N. Y., assignor
to National Biscuit Company, New York, N. Y.,
a corporation of New Jersey

Application August 25, 1934, Serial No. 741,427

12 Claims. (Cl. 206—44)

My invention pertains to cartons and particularly to cartons that are adapted to be used as shipping containers for small packages or articles and can be converted easily by the merchant into an attractive display and dispensing device.

My improved carton, as illustrated, is adapted to be filled with a number of small packages of merchandise, for example, with bakery goods such as the well known Barnum's Animals, Uneeda Biscuit, and the like. The carton has a weakened or tear line extending along three sides about midway of the two ends and the fourth side is scored to provide a hinge, these score and tear lines dividing the carton into two separable sections connected by the hinge. The packages are packed in the carton facing in opposite directions on the two sides of the tear line. One end of the carton is provided with a folding part or parts adapted to form an easel or inclined support for the carton. The carton is closed and sealed after being packed. When the merchant receives it, he will break or tear the carton along the tear line on three sides. This separates the carton into two sections connected by the hinge. One section is turned about this hinge until the two sections lie in contact. This exposes the packages in the two sections at what was originally the center of the carton. The easel flaps are then folded into position (or this may be done before the carton is broken) and the broken carton placed in inclined position, supported by the easel, on the counter or other place for display of the contents which now face all in the same direction in the two halves.

In the accompanying drawings, I have illustrated two forms that my invention may take, wherein

Fig. 1 shows in plan a single piece blank from which the carton may be formed.

Fig. 2 shows the carton formed from the blank and ready for filling.

Fig. 3 shows the carton filled and the flaps forming the easel partly folded down preparatory to sealing.

Fig. 4 shows the carton sealed ready for shipment.

Figs. 5 and 6 are perspective views of the end of the carton with the easel formed.

Fig. 7 is a perspective view of the broken carton supported on the easel.

Fig. 8 shows in plan a single piece blank from which a carton having a different form of easel may be made.

Fig. 9 shows the carton filled and the easel partly folded down preparatory to sealing.

Fig. 10 shows the carton filled and sealed ready for shipment.

Fig. 11 shows the carton with the seal broken and the easel raised.

Figs. 12 and 13 show the carton supported in display position.

As shown in Fig. 1, my improved carton preferably is made from a single piece blank, having front and rear panels 12 and 13, and two side panels 14 and 15 which are defined by score lines 16, 17, 18, 19, 20, and 21 on the blank. At one end the blank has a glue-flap 22, which preferably is notched at the center in alignment with a perforated tear line 23 extending across the side panel 15 about midway of its length and in alignment with a score line or hinge 24 on the rear panel 13 and with similar perforated lines 25 and 26 on the two panels 14 and 12. These perforated lines and score line divide the four panels into two sections each.

At one end, which is the bottom end when the carton is formed but is the top end of the blank in Fig. 1, the front, rear and side panels are provided with flaps 27, 28, 29, and 30, which are folded in and secured by glue to close the bottom end of the carton. I have shown these closing flaps rectangular in shape and adapted to be secured by glue but they may be made in any shape desired and secured by inter-locking tongues and slots.

At the top ends of the side panels 14 and 15, there are extensions which are divided to provide easel rings 36, 37 and load flaps 31 and 32, which flaps have interlocking tongues 33 and 34 to secure them in closed position. An easel flap 35 is secured to the top edge of the rear panel 13 and to the pair of easel wings 36 and 37 along score lines 38 and 39, the wings being connected to the tops of the panels 14 and 15 along the score line 16. The wings have diagonal score lines 40 and 41 along which they are adapted to be folded. The load flaps 31 and 32 do not extend the full width of panels 14 and 15 but a part of the width of the panels is taken up by the wings 36 and 37.

A securing flap or easel brace 42 is connected along the score line 16 to the top of the front panel 12. This flap has a score line 43 along which it can be folded and at its outer edge has a stop flap 44 connected to it along a score line 45.

When a carton is formed from this blank, it is folded along the score lines 18, 19, 20, and 21 and the glue flap 22 is secured to the free edge of the front panel 12, preferably on the inside of the panel so that the carton has a smooth exterior. The flaps 27 and 29 are next turned down

and then the flaps 28 and 30 which are secured together to hold the end closed. Usually the flap 30 will overlie the flap 28 so that the carton will have a smooth bottom on the outside but it is 5 immaterial which of these flaps overlies the other.

When the carton is assembled, as thus described, it will appear as in Fig. 2 and be ready for filling. If it is filled with package goods, it will be filled up to the weakened lines 23 and 26 10 with the fronts of the packages facing upward. This fills the carton half full if the tear lines are midway of the ends of the carton. The top half of the carton is then filled with the tops of the packages facing in the opposite direction or 15 downward. When the carton is filled, the load flaps 31 and 32 are turned inward and the tongues 33 and 34 interlocked to close the top end. The securing flap 42 is next turned down and bent backward along the score line 43, as 20 shown in Fig. 3. The easel wings 36 and 37 are then bent inward along the diagonal score lines 40 and 41 and the easel flap 35 folded down upon the flap 42, the wings 36 and 37 underlying the easel 35, the edge of which now lies adjacent to the 25 score line 45. The flap 44 is now folded over the easel flap 35 and a strip of gummed tape 46 or other suitable adhesive is applied as shown in Fig. 4 so as to hold the easel folded tightly down against the top of the carton.

When the merchant receives the carton, he 30 will break the seal along the dotted line 47 which coincides with the folded edge of the flap 44. The tape will be left adhering to the stop flap 44 and the easel flap 35 which will securely hold the two together. If desired, glue can be applied to 35 the inside of the flap 44 before the tape 46 is applied but ordinarily the adhesion of the tape to the flaps 35 and 44 is sufficient. The merchant now raises the flaps 35 and 42 to the position shown in Figs. 5 and 6 and the wings 36 and 37 40 are turned outwardly until their inclined free edges contact with the under side of the flap 42. This braces the easel 35 securely in position and prevents its collapse.

The merchant then breaks or tears the carton 45 along the readily fracturable lines 23, 25, and 26 and turns the one half back against the other along the hinged connection or score line 24 into the position shown in Fig. 7. The end of the carton I have been referring to as the top end of the 50 carton is now turned down so that it is raised on the easel and is supported in display position as best shown in Fig. 7. In this figure, the easel flap 35 is nearly vertical, sloping slightly toward the rear but is prevented from going back too 55 far by reason of its connection with the stop flap 44 and the end flap 42, the latter flap now being horizontal and placed directly on the counter or other fixture where the display carton may be placed. The packages in the two halves of the 60 carton now all face in the same direction because of their having been packed originally to face in opposite directions with respect to the tear line.

In Figs. 8 to 11, I have shown another embodiment of my invention in which the easel and top 65 sealing flaps are different. This carton is also best made from a single piece blank as shown in Fig. 8, which has front, rear and side panels 12, 13, 14, and 15 the same as in Fig. 1 and a glue flap 22 which has a notch in alignment with the 70 tear lines 23, 25 and 26 and the hinge or score line 24. The panels are defined on the blank by the score lines 16, 17, 18, 19, 20, 21. The bottom end of the carton, which is the top end of the blank, is closed by suitable flaps 27, 28, 29 and 30.

At the top ends, the side panels 14 and 15 are provided with load flaps 31' and 32' and the rear panel 13 has an easel flap 35 to which easel wings 36 and 37 are connected along score lines 38 and 39, the wings being also joined to the side panels 5 14 and 15 along the score line 16 and each of them having a diagonal score or fold line 40, and 10 41, the same as in the figures previously described. The front panel 12 has an easel securing flap 42' which in this case is of substantially the same width as the side panels 14 and 15, and together with the flaps 31' and 32' supports 15 the load in the carton.

The easel panel 35 has a glue flap 48 defined by a perforated line 49 along which the material 15 of the carton may be readily torn.

The blank is assembled to form the empty carton the same as in Fig. 1 and the carton is filled in the same manner with the packages facing in opposite directions with respect to the two sections of the carton. When the carton is filled, the flaps 31' and 32' are first turned inward and then the easel securing flap 42' is turned down and glued to them. This securely closes the top end of the carton as shown in Fig. 9. The wings 25 36 and 37 are then bent inwardly under the easel flap 35 which is pressed down upon the top of the carton and held in place by gluing the flap 48 to the flap 42' as shown in Fig. 10. When the merchant receives the carton, he breaks it along 30 the perforated line 49 and turns the easel up to the position shown in Fig. 11. He next tears or breaks the carton along the weakened line 23, 25, and 26 and turns the one half of the carton on the hinged connection into contact with the other 35 section as shown in Fig. 10. The carton is then placed in display position with one end of the carton and the easel 35 placed on the counter or other store fixture as clearly shown in Figs. 12 and 13. The wings 36 and 37 when straightened 40 out as shown in Figs. 11, 12 and 13 strengthen and prevent collapse of the easel panel 35.

It will be noted that the easel flaps 35 are shorter than the width of the side panels 14, 15 and that the wings 36, 37 or easel brace 42 prevent 45 the easel flaps 35 from being turned back beyond the plane of the rear panel 13, as best shown in Figs. 7, 12 and 13. This results in a rigid construction and enables the easel to support the carton in a very stable position. When 50 the carton is in display position, the merchandise is displayed through the open ends of the two sections of the carton where broken along the lines 23, 25, 26. The lower section is supported 55 on its front edge and by the easel flap 35, while the upper section is supported partly on the lower section and partly by its connection along the hinge line 24, as clearly shown in Figs. 7 and 12.

While I have illustrated and described two 60 forms that my invention may take, and while I have referred to the parts by specific terms, it will be understood that these are but illustrative of the invention and not to be taken as limitations. I claim as my invention all modifications 65 and equivalents thereof that may come within the scope of the following claims.

I claim:

1. A carton having four sides and a closed end, 70 load flaps for closing the other end of the carton, easel flaps hinged to the edges of the carton adjacent the load flaps, said easel flaps being foldable over said load flaps, and means for securing said easel flaps in folded position, said securing means being breakable to release said easel flaps, said 75

easel flaps being foldable on their hinge connections to form an inclined support for the adjacent end of the carton.

2. A carton having four sides and a closed end, 5 load flaps for closing the other end, easel flaps connected along one side to opposite edges of said other end, means for securing the free sides of said easel flaps together, the combined length of said easel flaps exceeding the width of the carton, 10 said easel flaps being foldable to overlie said load flaps, a seal for securing said easel flaps in folded position, said easel flaps upon breaking said seal being foldable into a triangular support for the adjacent end of the carton.

15 3. A carton having four sides and a closed end, load flaps for closing the other end of the carton, easel flaps overlying said load flaps, means for securing said easel flaps in folded position over said load flaps, said easel flaps upon breaking said 20 securing means being foldable to form an inclined support for the adjacent end of the carton, said carton being divided into two sections by a breakable connection in three sides and a hinged connection in the fourth side, said sections upon 25 breaking said breakable connection being foldable on said hinged connection with their sides in contact and the severed edges lying in the same plane.

4. A carton having four side walls divided into 30 two sections by a breakable connection and a hinged connection, said sections adapted to be turned on said hinged connection into side contact, means for closing one end of each section, easel forming means secured to the edges of one 35 of said closed ends and foldable over the closing means, severable means for securing said easel forming means in folded position, said easel forming means being foldable into an inclined support for said sections upon severance of said securing means.

40 5. A carton blank comprising front, rear and two side panels, a tear line extending across three of said panels and a scored line across the other panel in alignment with the tear line, end sealing flaps at the bottom end of said panels, load supporting flaps at the top ends of the two side panels, an easel flap hingedly connected to the top 45 end of the rear panel and having wings connected to the top ends of the side panels, a securing flap connected to the top edge of the front panel, and a glue flap on one of said front and rear flaps.

6. A carton blank comprising front, rear and two side panels, a tear line extending across three of said panels and a scored line across the other panel in alignment with the tear line, end sealing flaps at the bottom end of said panels, load supporting flaps at the top ends of the two side panels, an easel flap hingedly connected to the top 55 end of the rear panel and having wings connected to the top ends of the side panels, a brace flap secured to the top edge of the front panel, a stop flap secured to the top free edge of said brace flap and adapted to be secured to said easel flap.

7. A carton blank comprising front, rear and two side panels, a tear line extending across three 60 of said panels and a scored line across the other

panel in alignment with the tear line, end sealing flaps at the bottom end of said panels, load supporting flaps at the top ends of the two side panels, an easel flap hingedly connected to the top end of the rear panel and having wings connected to the top ends of the two side panels, a securing flap secured to the top of said front panel of a length substantially equal to the width of said side panels, and a securing flap secured to the free top edge of said easel flap along a weakened line. 10

8. A carton having front, rear, and two side walls, means for closing one end of the carton, flaps at the other ends of the side and front walls for closing the other end of the carton, an easel hingedly connected to the top of the rear wall and 15 the side walls at said other end, said easel being foldable over said front wall flap, and a glue flap secured to said easel along a weakened line and fixedly secured to said front wall flap.

9. A carton having four side walls divided into 20 two sections by a readily fracturable connection and a hinged connection, said sections upon breaking said readily fracturable connection being adapted to be turned on said hinged connection into side contact, means for closing one end of each section, easel forming means folded and overlying one of said closed ends, severable means for securing the folded easel forming means to said closed end, said easel forming means upon severance of said securing means being foldable 25 into an inclined support for said sections.

10. A display and dispensing device comprising 30 a carton formed in two sections connected by a hinged section and having abutting sides, each of said sections having a closed end and an open end, the two open ends lying in the same plane and being parallel to the closed ends, and an easel 35 engaging one of said closed ends and supporting both of said closed ends in inclined position so that said open ends lie in an inclined plane to 40 display merchandise contained therein.

11. A carton having front, rear and side walls, load flaps hingedly secured to the side walls at one end of the carton and foldable inwardly to close the end of the carton, an easel flap hingedly 45 secured to the rear wall at the said one end of the carton, easel wings hingedly secured to the two said side walls and to opposite edges of said easel flap, said wings being scored along diagonal lines whereby the easel flap and wings may be folded 50 flat over the load flaps, and means for securing said easel flap and wings in folded position, said securing means being breakable to release said easel flap and wings.

12. A carton formed from a single sheet of 55 material having front, rear and two side panels, said easel flap hinged to the edge of the rear panel, said easel flap extending the full width of the rear panel and being of less length than the width of the side panels, said side panels having extensions adjacent said easel flap, said extensions being divided to form load flaps and easel wings, said easel wings being connected by score lines to the ends of the said easel flap and to the said side panels.

BRUCE J. DAVIDSON. 65
